UNITED STATES PATENT OFFICE.

HENRY L. DOHERTY, OF NEW YORK, N. Y., ASSIGNOR TO DOHERTY RESEARCH COMPANY, OF NEW YORK, N. Y., A CORPORATION OF DELAWARE.

DOMESTIC HEATING STOVE.

Application filed September 8, 1920. Serial No. 408,970.

To all whom it may concern:

Be it known that I, HENRY L. DOHERTY, a citizen of the United States, residing at New York city, in the county of New York, 5 State of New York, have invented certain new and useful Improvements in Domestic Heating Stoves; and I do hereby declare the following to be a full, clear, and exact description of the invention, such as will 10 enable others skilled in the art to which it appertains to make and use the same.

This invention relates to domestic heating stoves and more particularly to a method of and apparatus for heating the interior of 15 buildings.

In heating a building by means of stoves or other fuel burning heaters placed in the rooms of the building, it is advantageous to obtain as much as possible of the heat of 20 combustion of the fuel in the form of radiant energy and to distribute the heat throughout the room by direct radiation rather than by conduction and convection. When convection currents are relied on for 25 distributing heat, the bodies of air heated by contact with the stove tend to rise to the upper part of the room and to form heat zones or strata which increase in temperature toward the upper part of the room. As 30 a result, the upper part of the room will be overheated before the lower part is heated to the desired temperature, and an unsatisfactory distribution of heat is obtained. When heat is transferred by radiation di- 35 rectly from the stove to the space to be heated, the heat is projected from the radiating body with equal force in all directions and may be directed or reflected in any direction or to any part of the room. Ac- 40 cordingly the tendency for heat to be carried to the upper part of the room by rising currents of air may be counter-acted by directing the radiated heat to the lower portions of the room and a better control of the heat 45 distribution may thus be obtained. Moreover, when radiation takes places from an incandescent or glowing body, a very pleasing lighting effect is produced which adds greatly to the attractiveness of this manner 50 of heating.

When gas is used as a fuel, it is, however, difficult to obtain the heat of combustion in the form of radiant energy. This is largely due to the fact that the heat produced by 55 the combustion of gas is not generated in

a body having a good radiating surface, as is the case with solid fuels, but is set free in a rapidly moving flame or body of gas of a very low radiating power. In the type of gas stoves heretofore used, the radiation 60 is further decreased through a cooling of the flame by the addition of cold air or inert gases of low temperature which enter the stove outside of the burner and mix with the flame. Since the rate of radiation of 65 heat is proportional to the fourth power of the absolute temperature of the radiating body, a small drop in temperature causes a relatively large drop in the quantity of heat radiated. As a result of the lower 70 radiation effects obtained in the type of stove heretofore used, the heat has been transferred from the stove and distributed throughout the room largely by conduction and by convection currents with a consequent 75 loss in efficiency and lack of uniformity of distribution.

A further loss of heat results from the entrance of an excess of air to the stove, because the volume of heated exhaust gases 80 is thereby increased and a correspondingly larger amount of heat passes to the chimney. Because of the difficulty of efficiently utilizing and readily controlling the distribution of heat formed by the combustion of gas 85 in the type of stoves heretofore used, the use of gas as a fuel for heating purposes has been greatly restricted, even in cases where only a temporary and moderate heat is re- 90 quired and where the use of gas would be particularly advantageous because of its convenience and cleanliness.

The primary object of the present invention is to provide a gas heating stove in which a maximum efficiency in the combustion 95 and distribution of heat is obtained.

Another object of the invention is to pro- 100 vide a gas fired heating stove in which a maximum amount of the heat of combustion of the gas is obtained in the form of radiant energy.

A further object of the invention is to provide a domestic heating stove in which the quantity of heat carried in the exhaust gases is reduced to a minimum.

A further object of the invention is to provide a method of heating with gas in which a maximum efficiency in combustion and in the distribution of heat is obtained.

With these and other objects in view, the 110

invention consists in the apparatus described in the following specification and particularly defined in the claims.

The various features of the invention are shown in the accompanying drawing, in which:

Fig. 1 is a sectional view in elevation of a gas fired heating stove, embodying a preferred form of the invention; and

Fig. 2 is a vertical sectional view of the stove, taken on the line 2-2 of Fig. 1.

The greatest efficiency in the utilization of the heat of combustion of the gas will be obtained when the minimum amount of air necessary for complete combustion is supplied to the stove. The addition of air over this minimum reduces the efficiency by cooling the flame and also by increasing the quantity of heat carried from the stove by the exhaust gases. In the present invention the losses caused through the entrance of an excess of air to the combustion chamber of the stove is prevented by supplying the air in a definite proportion to the rate of supply of the fuel gas and adjusting the proportion of air to gas to give the minimum amount of air necessary to insure the complete combustion of the gas. In proportioning the gas and air, the fuel gas passes under pressure through a gas meter, preferably of the wet type, and rotates the shaft of the meter at a rate proportional to the rate of flow of the gas. The shaft of the gas meter is connected to an air meter to force air to the combustion chamber at a rate proportional to the supply of gas. The combustion chamber in which the gas is burned is tightly closed to prevent the entrance of any additional air. By this means the gas and air enter the combustion chamber in a constant and definite proportion to insure perfect combustion and the volume of exhaust gases leaving the combustion chamber, and accordingly the heat passing to the chimney, is thereby reduced to a minimum.

The heat lost in the exhaust gases is still further decreased and the efficiency of the stove increased by transferring heat from the exhaust gases to the ingoing air by means of a suitable heat interchanger. By thus returning the waste heat of the exhaust gases to the combustion chamber, the temperature of the flame is raised and its heat radiating power correspondingly increased. In pre-heating the entering air, the air passes from the air forcing meter to the combustion chamber through a number of pipes or tubes surrounded by the hot products of combustion leaving the combustion chamber and is thereby heated before it enters the gas flame.

In the embodiment of the invention shown in the accompanying drawings, the meters for proportioning the gas and air are operated by the pressure of the gas supplied to the stove. For this purpose fuel gas under pres-

sure enters a meter chamber 10 through a pipe 12 and is delivered to one end of a gas measuring drum 14 above the level of a body of water contained in the chamber 10. The drum 14 is of the ordinary wet meter type and is rigidly mounted on a rotatable shaft 16 extending through the chamber 10. The gas entering the drum 14 through the pipe 12 is received in a chamber formed between an end wall 18 of the drum 14 and a wall 19 forming one end of a series of measuring pockets. The measuring pockets are formed by a series of helical blades 20, 22, 24 and 26 which extend from the cylindrical wall of the drum 14 inwardly under the level of water in the chamber 10 and connect with end walls 19 and 28 which extend from the edge of one blade to within a short distance of an adjacent blade. The pitch and the number of the blades 20-26, and the size of the end walls 19 and 28 are so adjusted to the level of water in the chamber 10 and the drum 14 that the front edge of one end wall, at the inlet end of the drum, will dip into the water in the chamber 10 before the rear edge of the preceding end wall, at the outlet end of the drum, rises above the surface of the water level. In this manner there is always one blade whose end walls extend below the surface of the water and seal the passageway through the drum. The pressure of the gas entering from the pipe 12 acts on the spiral blades to produce a resultant force which rotates the drum 14 and thus passes the bodies of gas enclosed between adjacent blades to the opposite end of the drum. The rotation of the drum will thus be proportional to the rate at which the gas passes through the drum. After passing through the measuring pockets of the drum 14, the gas is received in a compartment 29 formed in the chamber 10 above the water level and between walls of the chamber and a partition 30 extending from the top of the chamber into the body of water contained therein. From the compartment 29 the gas is delivered through a pipe 32 to a dome-shaped combustion chamber 34.

Air for supporting combustion of the gas in the combustion chamber 34 is measured and forced to the combustion chamber by the rotation of an air meter drum 40 mounted on the gas meter shaft 16 in the chamber 10. The meter drum 40 is rigidly fastened on the shaft 16 and is consequently rotated at the same rate of speed as the gas meter drum 14. Air enters the drum 40 through an inlet pipe 42 extending above the level of water in the drum 40 and is received between an end wall 44 of the drum and the end wall 45 of a series of measuring pockets. The measuring pockets are formed by a series of helical blades 46, 48, 50 and 52 which extend from the cylindrical wall of the drum 40 inwardly below the level of the water in

the drum 40 and connect with end walls 45 and 53 which extend from the edge of one blade to within a short distance of a preceding or following blade. The blades 5 46, 48, 50 and 52, and the end walls 45 and 53 are so proportioned in relation to the level of the water in the chamber 10 that the edge of one end wall, nearest the inlet pipe 42, will dip into the surface of the water 10 before the edge of the end wall of the preceding blade, at the outlet end of the drum, rises out of the surface of the water. As the edge of the inlet end wall dips below the surface of the water, it encloses a quantity 15 of air between the helical blade to which it is attached and the preceding blade, and as the drum continues to rotate, this air is forced to the opposite or outlet end of the drum.

20 The drum 40 is larger than the drum 14 inasmuch as the volume of air required for combustion will be several times the volume of the gas being burned. In cases where the stove is made for use with a particular 25 gas, and in which it is not desired to vary the proportion of gas and air, the diameter of the drums 14 and 40 will be the same, and the length of the drums will be proportional to the quantity of gas and air supplied to 30 the combustion chamber. With this construction, the proportion of gas and air will be constant regardless of the level of the water in the chamber 10. In case the stoves may be used with gases of different composition 35 which require different amounts of air for complete combustion, it will be necessary to vary the rates at which gas and air are supplied. This may be conveniently done by making the drums of different diameters, in which case the proportions of 40 gas and air may be varied by varying the level of the water in the chamber 10. From the opposite end of the drum 40 the air passes through slots 53 formed between the 45 edge of the end wall and a succeeding blade into an air receiving chamber 54 from which it passes into the heat receiving unit of a heat interchanger.

50 In the heat interchanger, the air is heated before passing to the combustion chamber by abstracting heat from the products of combustion leaving the combustion chamber. The heat interchanger comprises a chamber 55 positioned between the gas 55 meter 10 and the combustion chamber 34 and a series of tubes 60 forming the heat receiving unit of the heat interchanger, through which air passes from the chamber 54 to the combustion chamber 34. Hot 60 products of combustion from the combustion chamber 34 flow through the heat inter- change chamber 55 and are directed into contact with the heat receiving tubes 60 by means of baffles 62 and 64 positioned within 65 the heat interchange chamber 55. In pass-

ing through the heat interchanger, the air from the chamber 54 flows in a countercurrent direction to the hot exhaust gases from the combustion chamber 34. To this end, the air from the chamber 54 passes through 70 a connecting nipple 56 into a distributing manifold 58 in which it is distributed to a number of parallel tubes 60 in the chamber 55. The tubes 60 pass back and forth between baffles 62 and 64 in the heat interchange chamber and deliver the air to a receiving manifold 66 in the upper part of the chamber. From the manifold 66, the air which has been heated in its passage through the tubes 60 is delivered to the central part 80 of the combustion chamber 34 through an air delivery pipe 68 opening adjacent the end of the gas delivery pipe 32. The inter- changer or recuperator and the gas and air delivery pipes 32 and 68 are subjected to 85 much higher temperatures than those produced in an ordinary heating stove and are preferably made of Monel metal or of cal- orized or sherardized sheet metal in order to decrease or eliminate oxidation of the 90 metal.

95 By means of the above described inter- change of heat, practically all of the heat carried by the products of combustion is recovered and returned to the combustion chamber where it is added to that radiated directly to the room to be heated. The gases leaving the combustion chamber must neces- sarily be of the same temperature as the combustion chamber and will, therefore, 100 carry with them a considerable amount of heat. While the proportion of the quantity of heat radiated to the quantity carried by the hot gases is greater the higher the tem- perature, since radiation varies with the 105 fourth power of temperature, and the quantity of heat carried by the gases varies ap- proximately directly with the temperature, a very large amount of heat is nevertheless carried by the exhaust gases. Moreover, it 110 is not desirable to have gases at the tem- peratures prevailing in the combustion chamber pass directly to the exhaust flue or chimney. With the above interchange of 115 heat between the products of combustion and the ingoing air, the exhaust products of combustion are cooled to substantially at- mospheric temperature and the heat of the exhaust gases is thereby transferred to the ingoing air and returned to the combustion 120 chamber. The incoming air is thereby raised to approximately the temperature at which combustion takes place, and accord- ingly very little of the heat of combustion 125 is used in heating the incoming gases so that substantially all of the heat of combustion is radiated directly from the walls of the combustion chamber. The efficiency and completeness of the interchange of heat 130 is promoted by the fact that a minimum

quantity of gases is involved due to the proper proportioning of air and gas by the air and gas measuring devices.

The highly heated air from the pipe 68 mixes with the gas delivered by the pipe 32 and rises as a flame to the top of the combustion dome 34. On reaching the top of the dome, the flame is deflected downwardly and flows in a layer adjacent the inner wall 10 to the bottom of the dome. In passing downwardly in contact with the walls of the dome 34, the flaming gases heat the dome to incandescence and provide excellent conditions for the radiation of heat. The air and 15 gas entering through the pipes 32 and 68 are surrounded by a glowing layer of gases and by the heated walls of the chamber 34, which eliminates all danger of chilling of the gases and insures a rapid and thorough combustion 20 of the entering gases. By means of this construction complete combustion will have been obtained by the time the gases reach the upper part of the dome and the gases will be brought into contact with the walls of the 25 dome at the highest possible temperature and under conditions most favorable for the transfer of heat by radiation from the surface of the dome 34 toward the floor of the room to be heated. The dome 34 is 30 preferably constructed of silica, nicrom or other heat resisting material capable of being heated to incandescence without deterioration, and is preferably provided with a surface having a high radiating power or 35 emissivity in order to increase the quantity of heat radiated.

The exhaust gases from the chamber 34 containing a certain amount of residual heat pass downwardly into the heat interchange 40 chamber 55 between the baffles 62 and 64 and are brought into intimate contact with the air heating tubes 60. By this contact with the tubes 60 the residual heat of the waste 45 products of combustion passes to the air within the tubes 60 and is returned to the combustion chamber 34 while the residual gases are restored to substantially atmospheric temperature.

In a similar manner, the gas passing 50 through the gas supply tube 32 is preheated by the hot products of combustion. When a gas consisting essentially of hydrocarbons is used, in which case the volume of air necessary for complete combustion is several 55 times greater than the volume of gas, and there is a tendency for the gases to decompose and deposit carbon upon being heated, a comparatively short tube such as that shown in the drawings is employed. When 60 water gas or producer gas, or similar gases having a comparatively lower heating value and employing relatively smaller volumes of air and larger volumes of gas are used, a system of heat receiving tubes similar to the air tubes 60 should be employed.

When the fuel gas used in the stove contains a considerable amount of hydrogen or hydrocarbons, water vapor will be formed by the combustion of these gases. As the hot products of combustion are cooled in the 70 heat interchange chamber, the water formed in combustion will be condensed and will be collected in a lower part of the chamber. To remove this collected water a by-pass tube 69 connects the bottom of the chamber 55 to 75 the lower part of the meter chamber 10. An overflow pipe 70 is provided on the meter chamber 10 to prevent the accumulation of water from the pipe 69 and to maintain a constant level in the chamber. 80

It is preferred, in the interests of proper ventilation, that the waste products leaving the chamber 55 should be conducted to the outside atmosphere. The exhaust gases from the chamber are, therefore, ordinarily 85 passed through an outlet 71 to a chimney and exhausted to the atmosphere. In case it is not convenient to exhaust the flue products to the outside atmosphere, it will be found that the condensation of water in the 90 heat interchange chamber 55 will remove the greater part of the excessive humidity which is always present when open gas stoves are employed. The exhaust products will, accordingly, not have the deleterious 95 effects usually produced by exhaust products of gas stoves.

To direct the heat radiated from the dome 34 to the lower part of the room, a reflector 72 is supported over the dome 34 by means 100 of standards 74 resting on the heat interchange chamber 55. In case the reflector 72 concentrates the radiated heat to one spot in front of the stove, a screen 75 arranged to permit the heat rays to pass but having 105 a diffusing effect on the rays, may be provided. A door 76 is provided in the dome 34 through which the gas may be ignited in starting the stove. The door is closed when the stove is in operation, since the 110 proper amount of air for combustion is always delivered by the air meter 40.

Having described the invention, what is claimed as new is:

1. A method of heating dwellings or other 115 buildings comprising mixing air and gas in such proportions as will produce complete combustion of said air and gas, igniting said mixture in the interior of a closed combustion chamber of refractory readily incandescent material, maintaining a high flame temperature of said burning products in contact with the walls of said chamber, and reflecting the radiant heat of the combustion chamber in a definite desired direction. 120

2. A method of heating dwellings or other 125 buildings comprising mixing air and gas in such proportions as will produce complete combustion of said air and gas, igniting said mixture in the interior of a closed combus- 130

tion chamber of refractory readily incandescent material, passing the products of combustion into contact with the walls of said chamber, preheating air for combustion by a heat interchange with the hot products of combustion leaving the combustion chamber to develop a high flame temperature, and reflecting the radiant heat of the combustion chamber in a definite direction.

10 3. A method of heating dwellings or other buildings, comprising mixing air and gas in such proportions as will produce complete combustion of said air and gas, igniting said mixture in the interior of a closed combustion

15 chamber of refractory readily incandescent material, using gas under pressure for positively introducing said gas and air in a definite ratio into said chamber, passing the products of combustion into contact

20 with the walls of said chamber, maintaining substantially the maximum flame temperature by preheating the products for combustion with the hot products of combustion exhausting from the combustion chamber, 25 and reflecting the radiant heat of the combustion chamber in a definite direction.

4. A gas heating stove, comprising a combustion chamber of heat refractory material, a gas meter arranged to measure gas passing to said combustion chamber, an air meter driven by said gas meter arranged to pass measured quantities of air to said combustion chamber, an air conduit leading from said air meter to said combustion chamber, a 30 gas conduit leading from said gas meter to said combustion chamber, and an exhaust flue leading from said combustion chamber in heat conducting relation to said air conduit, and a reflector over said chamber.

40 5. A gas heating stove, comprising a combustion chamber, means for collecting gas and air in measured proportions, air and gas conduits leading from said air collecting means to said combustion chamber, and an exhaust flue leading from said combustion chamber in heat conducting relation to said conduits.

50 6. A gas heating stove, comprising a gas meter, an air measuring and forcing meter driven by said gas meter, a closed combustion chamber, means for introducing and mixing the gas and air from said meters within said chamber, and means for exhausting the products of combustion from said chamber.

55 7. The combination with a gas heating stove, of a gas measuring means, means operated by said gas measuring means for forcing air into said stove in a definite proportion to the passage of gas through said meter, a closed combustion chamber, a heat interchanger, means for passing air from said air measuring means through passageways in said heat interchanger, and means for forcing products of combustion from

said combustion chamber through said heat interchanger.

8. A gas heating stove, comprising a gas measuring means, an air measuring means driven by said gas measuring means and positioned to force air to said stove in definite relation to the passage of gas through said meter, a closed combustion chamber, having an exhaust gas passage at its bottom, means to mix the measured air and gas within the combustion chamber, and means for interchanging heat from the exhaust gases from said combustion chamber with the air passing from said air meter to said combustion chamber.

9. A gas heating stove, comprising a combustion chamber, a gas meter operated by gas passing to said combustion chamber, an air meter driven by said gas meter, arranged to force measured quantities of air to said combustion chamber, conduits for leading air and gas from said meters to said combustion chamber, an exhaust flue leading from said combustion chamber in heat-conducting relation to said air conduit, and a water by-pass pipe leading from the lower part of said exhaust flue to said gas meter.

10. A gas heating stove, comprising a meter chamber, an exhaust gas chamber on said meter chamber, baffles mounted in said exhaust gas chamber, a combustion chamber on said exhaust gas chamber, a gas pipe leading from said meter chamber to said combustion chamber, an air supply pipe leading from said meter chamber between said baffles to said combustion chamber, and inter-connected air and gas meters in said meter chamber adapted upon rotation to pass air and gas to said air and gas pipes respectively in definite measured proportions.

11. A gas fired heating stove, comprising a closed combustion chamber and means for positively delivering gas and air separately to the interior of said combustion chamber in a definite fixed ratio.

12. A gas fired heating stove, comprising a meter chamber, a shaft in said meter chamber, a gas meter drum on said shaft, an air meter drum on said shaft, a dividing partition in said meter chamber between said gas meter drum and said air meter drum and dividing said chamber into an air compartment and a gas compartment, a heat interchange chamber, a combustion chamber, a conduit leading from said air meter compartment through said heat interchange chamber to said combustion chamber, and means for exhausting gases from said combustion chamber through said heat interchanger chamber.

13. A gas fired heating stove, comprising a closed combustion chamber, a heat interchange means for interchanging heat between the exhaust gases from said combus-

tion chamber and the air entering said combustion chamber, and means for removing the moisture condensed from said exhaust gases in said heat interchange chamber.

14. In a gas fired heating stove, a dome-shaped combustion chamber, of ceramic refractory material capable of becoming incandescent at high temperatures, means for 10 delivering air and gas in measured proportions into the interior of said combustion chamber, means for withdrawing the products of combustion from the bottom of said combustion chamber, and a reflector over 15 said combustion chamber.

15. A method of heating dwellings or

other buildings comprising mixing air and gas in measured proportions to produce complete combustion thereof, igniting the mixture in the interior of a closed combustion chamber of a refractory readily incandescent material, passing products of combustion into contact with the interior walls of the chamber, and maintaining substantially the maximum flame temperature within the chamber by preheating the products for combustion with hot products of combustion exhausting from the combustion chamber.

In testimony whereof I affix my signature.

HENRY L. DOHERTY.
